Application December 4, 1953, Serial No. 396,262

4 Claims. (Cl. 121—121)

This invention relates to hydraulically operated driving units and has particular although not exclusive reference to hydraulically operated driving units for conveyors.

It is an object of the present invention to provide a hydraulically operated driving unit of improved design which is capable of efficient operation at low speeds.

According to the present invention a hydraulically operated unit comprises a stator having at least one set of cylinders and pistons and a rotor with internal cam surfaces which co-operate with the cylinders or pistons so that reciprocation of the cylinders or pistons produces rotation of the rotor.

In a preferred embodiment of the invention suitable for driving a belt conveyor the stator is made of a number of sections mounted on a shaft and formed with five or more or less sets of cylinders equally spaced around and projecting radially from its circumference. That shaft is hereinafter referred to as the main shaft. The sides of the cylinders of each set are slotted to accommodate a cross shaft against which bear pistons movable within the cylinders. The axis of each cross shaft is parallel with that of the main shaft and each shaft carries one set of bearings.

The bearings travel in cam tracks arranged internally of a hollow drum member which surrounds the main shaft and forms the rotor. The flow of hydraulic liquid to and from the cylinder is controlled by rotary valves mounted for convenience at each end of the main shaft.

As an example of the invention a driving unit suitable for a belt conveyor will now be described in greater detail with reference to the accompanying drawings of which:

Fig. 1 is a cross section of part of the driving member, and

Fig. 2 is a further cross section showing in part a control valve and cylinders.

The driving member has a stationary main shaft 1 with five sets of cylinders equally spaced around the circumferences of a stator 2 and projecting radially therefrom. One set only is shown in Fig. 1. Each set contains four cylinders 3 which are arranged so that one cylinder is adjacent each end of the shaft 1 with two cylinders at the centre. Each cylinder in each set is diametrically slotted for about one half of its length to accommodate a cross shaft 4 of which there are ten, two for each set of cylinders each arranged with its axis parallel to that of the main shaft 1. Slidable within each cylinder is a piston 5 whose head bears against that part of the cross shaft 4 inside the cylinder. The pistons are hollow and have deep skirts.

The cross shafts 4 are generally of circular cross section except for those portions 6 which lie inside the cylinders where the cross section changes to rectangular.

Between the outer and central cylinders each cross shaft carries a bearing race containing for example, roller bearings 7 and the outer race 8 of which bears against

2

a cam track 9 formed on the internal surface of a rotor in the form of a hollow drum 10.

The drum 10 encloses the assembly of main shaft and cross shafts and is mounted on the former by ball bearings 11 held between stator 2 mounted on the main shaft at each end thereof and internally extending flanges 12 bolted to the drum at each end. Also bolted to the internal flanges 12 are rotary inlet and exhaust valves 13, 14 (only one of each of which appears in Fig. 1) which coact with drillings 15 in the stator so that one controls the admission and the other the exhaust of hydraulic liquid fed to the cylinders. To protect the components inside the drum the latter has two further internal flanges 16 bolted with the flanges 12 to the drum 10 and each of which fits closely round the stator and has an internal pocket 17 in which fits a flexible seal of any suitable type.

Each set of cylinders has its own passage 15 in the stator 2, for example figure 1 shows that passage 15 is associated with the cylinders 3. Figure 2 shows other passages 15a—15d, each of which is associated with one of the other sets of cylinders.

Each control valve has two longitudinal passageways, for example, valve 13 has passageways 13a (Figure 1) and 13b (Figure 2) providing communication from an inlet 18a in an end member 18 mounted on the main shaft 1 via an annular groove 13c to an outlet port 13d and that one of the passages in the stator in line with this port.

30 The exhaust valve 14 is constructed in a manner identical with that of the inlet valve 13 but is arranged on the shaft 1 so that there is a time lag between the admission of hydraulic liquid via the inlet 18a to a set of cylinders and the exhausting of the liquid via the exhaust valve 14. As the inlet and exhaust valves are secured to the hollow drum 10 and rotate therewith hydraulic liquid is admitted to each of the sets of cylinders in turn and after a predetermined interval exhausted from each of the sets of cylinders.

35 The cam tracks 9 inside the hollow drum 10 are elliptical so that as hydraulic liquid under pressure passes into the sets of cylinders the pistons are forced out and the drum is caused to rotate and so drives the belt of a belt conveyor which passes over its external surface.

40 It will be appreciated that the belt is driven directly thus avoiding drive couplings and speed reduction units as the speed of rotation of the drum can be very low and can be varied by variation of the volume of liquid delivered to the cylinders. In addition the driving power of the unit may be changed by altering the pressure of the liquid delivered. Reversal of the direction of rotation is achieved by reversing the application of the hydraulic fluid.

45 Any number of drums as described above can be assembled into a multi-drive head. Such a head would continue to drive even if one unit thereof failed. The hydraulic liquid can be supplied from one central pump or each unit may have its own pump. The pump or pumps may be positioned some distance from the driving head as working or installation conditions required. A relief valve may be fitted to the hydraulic supply system to prevent damage due to overloading.

50 The shock load on a belt due to the starting is very much reduced with the driving unit as the change from start to full speed can be made very gradually.

55 For ease of manufacture the stator 2 may be built up of a number of sections which are fixed to a main shaft by a key or by any other suitable means (not shown). Conveniently each section may contain one cylinder of each set joined by webs 19 as illustrated in Figure 1. Obviously the size and power of the driving unit can be increased by increasing the number of sections.

The invention is not restricted to the exact construction illustrated, but what we claim and desire to secure by Letters Patent is as follows:

1. A hydraulically operated driving unit comprising a stator having a plurality of sets of power developing means arranged radially, each set including at least two parallel cylinder and piston assemblies, one of the members of each set being fixed to the stator and the other being movable relative thereto, a cross-shaft for each assembly against which the movable member of the assembly bears, bearings on the cross-shafts, a plurality of passages in said stator, each passage being in communication with the cylinders of a different set of assemblies, and a surrounding hollow rotor, at least one cam surface on the internal face of said rotor for co-operation with said bearings on the cross-shafts of the sets of assemblies in the same radial group to cause rotation of said rotor in synchronism with the reciprocation of said movable assembly members, control valves secured at each end of the rotor and rotatable therewith to control the admission of exhaust of hydraulic liquid from and to an inlet and an outlet member fixed to the stator.

2. A hydraulically operated driving unit comprising a stator having a plurality of sets of power developing means arranged radially, each set including at least two parallel cylinder and piston assemblies, one of the members of each set being fixed to the stator and the other being movable relative thereto, a cross-shaft for each assembly against which the movable member of the assembly bears, bearings on the cross-shafts, a plurality of passages in said stator, each passage being in communication with the cylinders of a different set of assemblies, and a surrounding hollow rotor at least one cam surface on the internal face of said rotor for co-operation with said bearings on the cross-shafts of the sets of assemblies in the same radial group to cause rotation of said rotor in synchronism with the reciprocation of said movable assembly members, an inlet control valve, an outlet control valve, flanges securing said valves to said rotor at each end thereof, inlet and outlet members on

said stator connectable by said control valves to each of said passages in turn.

3. A hydraulically operated driving unit comprising a stator having a plurality of sets of power developing means arranged radially, each set including at least two parallel cylinder and piston assemblies, one of the members of each set being fixed to the stator and the other being movable relative thereto, diametral slots in each cylinder of each assembly, a cross-shaft in the diametral slots of each assembly and in engagement with the pistons of the assembly, bearings on the cross-shafts, a plurality of passages in said stator, each passage being in communication with the cylinders of a different set of assemblies, and a surrounding hollow rotor, at least one cam surface on the internal face of said rotor for co-operation with said bearings on the cross-shafts of the sets of assemblies in the same radial group to cause rotation of said rotor in synchronism with the reciprocation of said movable assembly members, control valves secured at each end of the rotor and rotatable therewith to control the admission of exhaust of hydraulic liquid from and to an inlet and an outlet member fixed to the stator.

4. A hydraulically operated driving unit according to claim 1 in which said control valve is provided with an annular groove to which said hydraulic fluid is admitted, two diametrically opposed longitudinal passageways and two outlet ports each of which is joined by one of said passageways to said annular groove.
